CLAIM

The ornamental design for an angled pressure switch, as shown and described.

DESCRIPTION

FIG. 1 is a top, front, right isometric view of an embodiment of an angled pressure switch;

FIG. 2 is a bottom, back, left isometric view of the embodiment of the angled pressure switch shown in FIG. 1;

FIG. 3 is a front view of the embodiment of the angled pressure switch shown in FIG. 1;

FIG. 4 is a right side view of the embodiment of the angled pressure switch shown in FIG. 1;

FIG. 5 is a back view of the embodiment of the angled pressure switch shown in FIG. 1;

FIG. 6 is a left side view of the first embodiment of the angled pressure switch shown in FIG. 1;

FIG. 7 is a top view of the embodiment of the angled pressure switch shown in FIG. 1; and,

FIG. 8 is a bottom view of the embodiment of the angled pressure switch shown in FIG. 1.

The broken lines shown in the drawings represent portions of the angled pressure switch that form no part of the claimed design.

1 Claim, 6 Drawing Sheets
